UNITED STATES PATENT OFFICE

2,681,018

INTERFITTING WALL AND DOOR
CONSTRUCTION

Ralph E. McClellan, Toledo, Ohio, assignor to
Meilink Steel Safe Company, Toledo, Ohio, a
corporation of Ohio

Application January 15, 1951, Serial No. 206,111

8 Claims. (Cl. 109—74)

1

This invention relates to storage receptacles for protection of contents of the receptacles from hazards of heat and impact.

This invention has utility when incorporated in safes for valuables. The invention is directed toward maintaining sealed off storage protection of the safe contents from fire, water, and drops or falls, as from building collapse.

Referring to the drawings:

Fig. 1 is a front elevation, a portion being broken away, of a safe having features of the invention incorporated therein;

Fig. 2 is an enlargement in fragmentary section showing an assembly for the caster-carrying skirt with the safe shell bottom;

Fig. 3 is a plan view of a caster-carrying bracket with the wheel and a portion of the skirt;

Fig. 4 is a fragmentary view of impact-distorted bracket, broken caster or wheel, and safety body connecting strip portion;

Fig. 5 is a section of a closed door frame at the jamb, with adjacent portions of the door and safe housing;

Fig. 6 is a view looking directly into a strip portion of the jamb, the strip showing the slots of the yield region; and

Fig. 7 is a view similar to Fig. 6 in which there is distortion of the slotted region of the strip.

The safe 1 has a door 2 with hinges 3. On the door front is shown the exposed portion of a combination lock 4 and a door-bolt operating handle 5 (Fig. 1).

The receptacle or safe 1 has an inner sheet metal wall 6 (Fig. 5) and an outer shell or sheet metal wall 7. The safe front door opening has jamb rib 8 and groove 9.

The door 2 has an inner sheet metal wall 10, an outer wall or shell 11. Between the door inner and outer walls 10, 11, there is a door frame forming a rib 12 and a groove 13. The configurations are such that the rib 12 is complementary to the jamb groove 9 and the frame groove 13 is complementary to the jamb rib 8. Between the inner walls 6, 10, and the outer walls or sheets 7, 11, is insulation filler 14 providing safe reinforcement and fire resistance properties to the completed safe.

As bounds for the rectangular base or bottom of the safe 1, there is a bounding flange, rim or skirt 15 (Figs. 1, 2, 4), having a front or beneath-the-door portion 16, a back portion 17 and ends 18. At each corner of the skirt is a bracket. Bracket plate portion 19 (Fig. 1) is flatwise toward the safe base or bottom. From the portion 19 a tongue 20 (Fig. 2) extends downward to

2

the bracket body portion 21. Coplanar from an end of the portion 21 is an extension 22 (Figs. 2, 3, 4) to a flange 23. Spot welds 24 anchor the flange 23 with the end wall 18 of the skirt 15. Remote from the flange 23, the body portion 21 has an offset 25 to a flange 26 parallel to the body portion 21. The flange 26 has welds 24 to anchor this flange 26 with the skirt front wall 16. An axle 27 journals a caster or wheel 28. The axle has one end thereof in the body portion 21 and the other end riveted in the skirt wall 16. The four brackets with their wheels are thus assembled with the skirt to form a unit. This unit may be connected to the safe base or bottom by bolts 29 (Fig. 3).

The downward offset of the extensions 22 from the portion 19 provides a clearance 30 (Figs. 1, 2) from a bottom flange 31. There is a similar downward offset for the portion 25. This leaves the relatively weaker tongue 20 therebetween.

The inner region of the jamb is herein shown as anchored by spot welds 24 to the inner wall 6 of the housing or safe. Remote from this assembly with the inner wall 6, the jamb has outward from the groove 9 a flange 32, inward from and parallel to the outer wall 11 of the safe door 2. The flange 32 in its extent toward the safe outer wall 7 has an offset 33 to just beyond the plane of the door wall 11 and just clear of outer edge 34 of the door 2. Approximately co-planar with the door wall 11 and parallel to the flange 32, the jamb has a bounding strip 35.

From the door opening, the safe outer wall has a portion 36 connected by convex or rounded corner 37 to the outer safe wall 7. An inner section or cove 38 has spot welds 24 providing anchoring connection thereof with the wall 7 inner side. In the extent of the cove 38 past the corner 37 there is a slight inward offset 39 from which extends a flat section 40 to the offset 33 and parallel to the strip 35 and the portion 36. The portions 36, 40, from the pocket bottom 39, provide a closed bottom pocket for the strip 35.

Along and extending lengthwise of the strip 35 portion of the jamb are slots 41, 42 (Fig. 6). The portion 36 has ports or holes 43 (Fig. 5) for arc welds 44 (Fig. 6) to anchor the portion 36 with the strip 35.

The pair of parallel upwardly extending sides 50 of the door opening, connected at the top, form a U-shaped channel pocket for the strip 35. The safe bottom outer wall 7 has spot weld anchorage with the bottom flange 31. The safe reinforcing insulation filler 14 may be introduced thru the open back and the back wall later applied. In-

asmuch as the safe bottom should be assembled before charging the safe with the filler 14, the inner wall 6 may or may not be assembled with the jamb prior to putting the bottom in position. For assembling the four sided door jamb, the safe may be inverted so that the strips 35 may be easily slid into said U-shaped channel pockets. The four sided jamb thus introduced into the U-shaped channel pocket, leaves the free ends of the parallel U-shaped channel open, which ends are then closed or covered by the safe bottom 7. Arc welds 44 at the ports 43 may now anchor together the assembly for the safe, which assembly is now ready to have the filler 14 charged thereinto.

This construction gives protection from extreme hazards, such as from fire and external impacts that might occur by the dropping of the safe through a building when a burning building collapses. During such hazards the sealing effectiveness of the door is maintained because of the inventive structure here disclosed. With the safe generally in an upright position its bottom would be subjected mostly to the greatest impact after such a fall. Thus, the brackets for supporting the wheels 23 aid in reducing the effect of this impact by being distorted under pressure. The metal boundary for the door frame including the pocket 39 and the jamb including the strips 35, respond to extremes in temperature expansion to prevent the tongue in groove joints 3, 13, 9, 12 from parting. An illustration of the distorted safe structure after being exposed to heat and impact is shown in Figs. 4 and 7, wherein the slots 41' and 42' are distorted from those shown in Fig. 6, and the tongue 25 is shortened and bent, and wheel 28' is ruptured.

What is claimed and is desired to secure by Letters Patent is:

1. In a wall construction comprising two sheets, a closed connection between adjacent longitudinal portions of said sheets, said connection comprising: two parallel sides forming an open pocket along and attached to one of said portions of one of said sheets, a strip attached to the adjacent portion of the other of said sheets, said strip fitting into said pocket and being anchored to said pocket near its bottom, and said strip having longitudinal slots parallel to said longitudinal portions covered by at least one side of said pocket, thereby permitting relative movement due to contraction and expansion between said sheets in said pocket without opening the connection between said portions and without rupturing the anchorage in said pocket.

2. A wall construction according to claim 1 wherein said sheets comprise the inner and outer walls of a safe.

3. A wall construction according to claim 1 wherein said strip has a plurality of parallel overlapping rows of slots.

4. A wall construction according to claim 1 wherein said sheets are made of metal.

5. A wall construction according to claim 1 wherein said anchorage of said strip in said pocket is at spaced points between said slots along said strip.

6. A doorway comprising: a door having an edge, a jamb for said edge, a tongue and groove interlock between said jamb and said edge, a frame for said jamb, said frame having a channel pocket, a strip extending from said jamb into said channel pocket, means for anchoring said strip near the bottom of said pocket, said strip having longitudinal slots transversely yieldable between said jamb and said anchoring means to permit expansion and contraction between the parts of said doorway without affecting the tongue and groove interlock.

7. In a wall construction comprising two sheets, a closed connection between adjacent longitudinal portions of said sheets, said connection comprising: a strip attached to the adjacent portion of one of said sheets, said strip overlapping and being anchored to the adjacent portion of the other of said sheets near the edge of said strip, and said strip having longitudinal slots parallel to said longitudinal portions, said slots being covered by said other adjacent portion, thereby permitting relative movement due to contraction and expansion between said sheets without opening the connection between said overlapping strip and longitudinal portion and without rupturing the anchorage between said sheets.

8. A doorway comprising: a door having an edge, a jamb for said edge, a tongue and groove interlock between said jamb and said edge, a frame for said jamb, said frame having a flange, a strip extending from said jamb adjacent said flange, means for anchoring said strip near its edge to said flange whereby said flange overlaps said strip, said strip having longitudinal slots transversely yieldable between said jamb and said anchoring means to permit expansion and contraction between the parts of said doorway without affecting said tongue and groove interlock.
